UNITED STATES PATENT OFFICE.

HARRY A. TAYLOR, OF NEW YORK, N. Y.

PLACKET-CLOSURE.

SPECIFICATION forming part of Letters Patent No. 738,374, dated September 8, 1903.

Application filed October 29, 1902. Renewed July 7, 1903. Serial No. 164,605. (No model.)

To all whom it may concern:

Be it known that I, HARRY A. TAYLOR, a citizen of the United States, and a resident of the borough of Manhattan, county of New York, city and State of New York, have invented certain new and useful Improvements in Placket-Closures, of which the following is a specification, reference being had therein to the accompanying drawings, in which—

- 10 Figure 1 is a view of a portion of a skirt, showing the placket members separated and the placket-closure in position; Fig. 2, an elevation of one of the closure-strips detached. Figs. 3, 4, and 5 are detail elevations of different forms of stiffening-sections; Fig. 6, a transverse sectional view of one strip, and Fig. 7 a similar view showing a slightly-different arrangement of fastening and covering means.
- 20 The object of this invention is to provide a placket-closure which will effectually prevent any gapping of the members of the placket when the skirt is pulled toward either side or when the wearer is seated.
- 25 The invention consists in forming a closure-strip of a series of sections, each section carrying one member of a fastening device and connecting the adjacent ends of these sections by flexible hinge-like joints. These sections
- 30 are of sufficient stiffness or rigidity to prevent the members of the placket separating or gapping between adjacent fastening devices, and the flexible hinge-like joints between the sections permit the placket members to be freely
- 35 moved in any direction when connected together without any separation of the members. It is of course obvious that the sections composing the closure-strip may be made of any suitable material and that any
- 40 suitable flexible means may be used for connecting said strips together.

Referring to the various parts by numerals, 1 designates the inner member of the placket, 2 the outer member thereof, and 3 the skirt-band.

Secured to the outer face of the inner member 1 of the placket and to the inner face of the outer member is a closure-strip 4, each strip being composed of a series of independent stiffening-sections 5, the adjacent ends of these sections being connected together by means of short links or rings 6. As shown

in Fig. 1, these sections are short strips of flat flexible and resilient material—such as sheet metal or celluloid or similar material—55 and each section carries near its lower end one member 7 of a two-part fastening device. As shown in Fig. 1, these sections have cut-out portions to lighten the same and to increase their flexibility. This series of sections is preferably covered by a strip 8 of suitable material, such as fabric, and are secured to the placket members, so that the parts of the two-part fastening devices which are carried by one strip will register with the 65 corresponding or coacting parts of the fasteners on the other strip. It will be thus seen that when the members of these fastening devices are interlocked the placket members will be closely secured together at one point 70 at least on each independent section and that the joints between the sections will permit the members of the placket to be carried sideways toward either side or to be buckled vertically without causing any gapping between 75 the fastening devices, the said sections being sufficiently rigid to prevent the members of the placket separating.

In Fig. 3 the sections are shown as formed of twisted wire, the wires near each end of each section being formed into loops 9, which receive one member of a two-part fastening device. These wire sections are connected together by means of links 10 in a manner similar to that shown in Fig. 1. These wire 85 sections are quite stiff and may carry fastening devices in each end thereof instead of only at one end, if desired.

In Fig. 4 the sections are formed of a single strand of flexible and resilient wire, which 90 is bent back and forth to form a flexible and resilient section, the wire at each end of the section being formed into rings 11, within which are secured one member 12 of a two-part fastening device. The sections of this 95 strip are not connected together by means of rings, but they are secured to a strip of fabric 13, the fastening devices 12 aiding in securing the sections to the fabric, as shown in Fig. 6, and the fabric forming the flexible 100 connecting means between the sections.

It is obvious that the rings 6 and 10 of Figs. 1 and 3 may be dispensed with, if desired, and the fabric-coverings for said sec-

tions serve the purpose of the flexible connecting means between the strips. The metallic ring-connecting means forms a stronger connection between the sections than the fabric and for some conditions may be preferable to the simple fabric connection shown in Fig. 4.

In Fig. 5 the stiffening-section is shown as formed of wire arranged in the form of a link 14, small coils 15 being formed along the longitudinal edges of said link to increase the resilience of the section. Parts 16 of the fastening devices are secured at the ends of the link, and a strip 17 of fabric is secured there-
to in any suitable manner. The links are separated longitudinally a short distance, and the fabric strip 17 forms a flexible means by which the sections are connected together.

In Fig. 7 the fastening device is secured directly to the stiffening-section, and a tubular covering 18 is secured to said section. In this manner of arranging the parts the sections may be connected by links, as in Figs. 1 and 3, or the covering material may form the flexible connection between the sections.

It will thus be seen that this placket-closure will be very flexible, and the member of the placket may be moved in practically any direction when the two strips are fastened together without any gapping between the said members. It will also be seen that the fastening devices will be rigidly held in position and will not be loosened or torn from the sections by the strain of separating the two members of the fasteners.

One of the great objections to using the ordinary two-part snap or glove fastener on garments is that the strain of separating them weakens the threads by which the fasteners are secured to the garment. It will be readily seen that in this case fasteners are very securely anchored within the closure-strips and are so securely fastened as to be able to stand whatever strain may be brought upon them.

Having thus described my invention, what I claim as new, and desire to secure by Letters Patent, is—

1. A placket-closure device comprising a pair of closure-strips each strip being formed of a series of stiffening-sections arranged end to end, each section carrying one part of a two-part fastening device, whereby when the two parts of the fastening devices are connected together the stiffening-sections of the two members will be connected together one upon the other, said connected sections being held by the fastening devices against independent longitudinal movement.

2. A placket-closure device comprising a pair of closure-strips each strip consisting of a series of resilient stiffening-sections arranged end to end, one part of a two-part fastening device connected to each of said sections, said fastener being located within the longitudinal edges of the stiffening-sections, whereby when the two parts of the fastening device are connected together the sections

will lie one upon the other and will be held against independent longitudinal movement.

3. A placket-closure device comprising a pair of closure-strips, each strip being formed of a series of resilient stiffening-sections, one part of a ball-and-socket fastener secured to each of said stiffening-sections, said fasteners being located within the longitudinal margins of the stiffening-sections, whereby when the two parts of the fasteners are connected together the sections will lie one upon the other and will be held against independent longitudinal movement.

4. A placket-closure device comprising two closure-strips, each strip being formed of a series of resilient stiffening-sections formed of wire extended back and forth to form a strip of suitable width, one part of a two-part fastener being secured to each of said stiffening-sections.

5. A placket-closure strip formed of independent resilient sections arranged end to end, one part of a two-part fastener secured to each of said stiffening-sections, and a flexible supporting-strip for said sections, the fastening devices extending through said supporting-strip.

6. A placket-closure strip formed of independent stiffening-sections arranged end to end, one part of a two-part fastener secured to each of said stiffening-sections, and a flexible supporting-strip for said sections, the fastening devices extending through said supporting-strip.

7. A placket-closure strip formed of a series of independent resilient stiffening-sections formed of wire, one part of a two-part fastening device secured to each of said stiffening-sections, and a flexible supporting-strip for said stiffening-sections, the fastening device extended through said supporting-strip.

8. A placket-closure strip formed of a series of independent resilient stiffening-sections arranged end to end and formed of wire extended back and forth to form a flat strip of suitable width, one part of a two-part fastening device secured to each of said stiffening-sections within the longitudinal margins of said sections, a flexible supporting-strip for said stiffening-sections, the fastening devices extending through said supporting-strip.

9. A placket-closure strip formed of independent resilient sections arranged end to end, one part of a two-part fastener secured to each of said stiffening-sections, and a flexible tubular strip containing said stiffening-sections, the fastening devices extending through said tubular strip.

10. A placket-closure strip formed of a series of independent resilient stiffening-sections formed of wire, one part of a two-part fastening device secured to each of said stiffening-sections and a flexible tubular strip containing the stiffening-sections, the fastening devices extending through said tubular strip.

11. A placket-closure device comprising a pair of members adapted to lie one upon the other and each consisting of a fabric-support and a series of stiffening-sections arranged end to end and separated sufficiently to form a flexible joint between each pair, the sections and joints of one member coming opposite the sections and joints of the other member when the members are superposed, and temporary fastening devices arranged at in-

tervals along each member, the fastening devices being connected to and carried by the stiffening-sections.

In testimony whereof I hereunto affix my signature, in the presence of two witnesses, 15 this 28th day of October, 1902.

HARRY A. TAYLOR.
